UNITED STATES PATENT OFFICE.

EDWIN PEAR MONROE, OF NEW YORK, N. Y., ASSIGNOR TO THE UNITED STATES METALLIC PACKING COMPANY, OF PHILADELPHIA, PA.

METALLIC ROD PACKING.

SPECIFICATION forming part of Letters Patent No. 293,189, dated February 5, 1884.

Application filed October 6, 1882. (No model.)

To all whom it may concern:

Be it known that I, EDWIN PEAR MONROE, of the city, county, and State of New York, have invented a new and useful Improvement 5 in Metallic Rod Packings for Valve and other Rods, of which the following is a specification.

The invention is more especially adapted to valve-rods for locomotives, and has for its object to produce a more simple and readily-adjusted packing than has hitherto been in use, and which is also self-adjusting to compensate for wear and for irregularities in the movement of the rod.

The invention consists, first, of an annular 15 packing-receptacle which surrounds the rod, and is contained in the stuffing-box. The said receptacle has a zone-shaped or spherical cavity, in which the packing-rings are contained, and its outer face is in contact with the inner 20 side of the stuffing-box cover. A tapering spiral spring abuts against the packing-rings, holding them in the socket in their receptacle, and at the same time pressing said receptacle 25 snugly against the inner side of the stuffing-box cover. The inner end of the spring abuts against a sleeve or support, which surrounds the rod and is inserted in the end of the valve-chest. Said support has an inner lining of 30 Babbitt or other anti-frictional metal, and the same material is interposed between the stuffing-box cover and packing-receptacle.

In Letters Patent Nos. 245,967 and 246,185, granted to me August 23, 1881, I have shown and described certain features which are embodied in my present application. In No. 245,967 is contained the annular packing-receptacle bearing against the stuffing-box cover and having a zone-shaped socket to receive packing-rings, and also a spring for holding 40 the rings and their receptacle in place. Said spring is, however, short and not tapered, and the bearing at its rear end is differently constructed from that shown in my present application. In No. 246,185 there is no separate moving packing-receptacle, and various other differences are present, which will be obvious upon inspection.

In the accompanying drawings, Figure 1 is a vertical longitudinal section of my device. 45 Fig. 2 is a transverse section on the line *xx*. Fig. 3 is a plan and section, and Fig. 4 is also

a plan and section of the two packing-rings, respectively, which two rings I preferably use in the device described in lieu of the single ring.

55

In the drawings similar letters of reference indicate like parts.

A represents the end of the valve box or chamber, through which passes the rod B. In said end is inserted an annular support, C, 60 preferably of brass, and provided, as shown, with a feather, which prevents its rotation in its seat. The said support has an interior lining, D, of Babbitt or other anti-friction metal. I have shown this lining as made 65 thicker at that portion which lies beneath the rod when the support C is in place in the valve box or chamber, the object being to present a greater amount of metal at the place where the most wear occurs. The outer end 70 of the support C is enlarged and a recess, E, is provided therein, which receives and aids in holding the lining D.

F is a spiral spring, made in tapering form. At each end of said spring two of the turns 75 are pressed together, so as to lie in contact. The object of this is to form a solid bearing or abutment at each end of the spring from the material of and integral with the spring itself.

I do not limit myself to the pressing together of but two turns of the coil at each end, inasmuch as this feature will in some measure depend upon the nature of the wire of which the spring is formed, springs which are of more flexible construction generally 80 requiring the contact of a greater number than two coils to make a solid bearing or abutment.

The outer faces of the last turns of the coils at each end of the spring, when the latter is 90 made of round wire, are preferably flattened, so as to lie in close contact with adjacent parts of the device. The larger end of the coiled spring F is placed in contact with the support C or with the base of the stuffing-box. The 95 smaller end of the said spring may be provided with a follower, G, as shown. This follower comes in contact with and is caused by the expansive tendency of the spring F to press upon the packing-rings H and I. The 100 packing-ring H is shown in Fig. 3, and the packing-ring I in Fig. 4. They are made of

Babbitt or other anti-friction metal, and are preferably slit, as shown. They are made spherical or rounded in exterior form, so as to conform to the shape of the spherical, rounded, 5 or cup-shaped socket of the packing-receptacle J. The rod passes, as represented in Fig. 1, through the spring F, the rings H and I, and the packing-receptacle J.

Owing to the spherical shape of the bearing-surface between the packing-receptacle J and the packing-rings H and I, the latter are perfectly free to rock in any direction, while their inner bearing-surfaces will remain always in contact with the rod B; and since the 15 internal bearing-surface of the receptacle J is of larger diameter at one than at the other end, the packing-rings, when pressed into the same, will quickly and easily be wedged or contracted by the said surface into closer contact with the rod.

In the face of the packing-receptacle J, I form a groove, in which I place a ring of Babbitt metal, K. The face thus babbitted comes in contact with an opposite face or shoulder 25 of a recess, L, in the stuffing-box cover M.

I do not limit myself to the specific arrangement of the Babbitt-metal ring and packing-receptacle here shown, inasmuch as the same may be varied without departing from the 30 purpose or principle of the invention by inserting the ring in an annular groove in the material of the cover M, in lieu of in the face of the packing-receptacle J, the object sought being simply the application of the anti-frictional metal to the two bearing-surfaces—namely, the surface of the packing-receptacle and the surface of the cover, which are in contact.

The diameter of the recess L in the cover 40 M is greater than the diameter of the packing-receptacle J to a sufficient extent to enable the latter to have lateral play therein in all directions. The rod B passes through the recess L and the aperture N in the cover M. Said aperture is of greater diameter than the 45 rod B, so that said rod may have lateral play therein. It will now be apparent that the packing-receptacle J being free to slide on the cover M in the recess L, it will follow the rod B in any lateral deviation which said rod may take from a right-line movement.

The stuffing-box cover I have shown as made in two parts, M and O. While I do not limit myself to this particular arrangement, 55 inasmuch as the cover might be made in a single piece, instead of being divided, or might consist of the part M only, I consider the construction shown as advantageous, for the reason that the insertion of the part O enables the cover to be conveniently lengthened. The result of this is to separate widely the packing-rings and the support C, which are the two surfaces against which the rod bears, so that that part of the rod which reciprocates 60 in the support C does not also move in the packing-rings, and vice versa, and thus the wear is distributed along two portions of the

length of the rod, instead of being received on one and the same portion, as otherwise would be the case.

The parts M and O of the cover are secured to the valve box or chamber by bolts Q, and the part M is provided with an internal brass lining, P, the function of which is to provide a wearing-surface for co-operation with the periphery of the packing-receptacle J. Around the parts of the cover and between the flanges thereon I place a sheet-iron envelope or jacket, R, which protects and gives a neat finish to the exterior of the stuffing-box.

It will be obvious that any lateral deviation of the rod B from a right-line movement cannot impair the tightness of the packing bearing thereupon, for the reason that the packing and the parts in relation therewith are 85 capable of automatically adjusting themselves in exact accordance with the amount of deviation taking place; and this effected, first, by the wearing of the babbitt lining the support C conformably to the new direction of motion 90 of the rod; second, by the self-adjustment of the packing-rings through their rocking or turning in their spherical seat as they follow the rod in its change in lateral position; and, third, by the self-adjustment of the packing-receptacle J, which also moves laterally with the rod. I thus obtain a metallic packing of simple construction which is self-adjusting, and thus preventive of the large waste of steam due to the wear and leakage of other forms of 100 packing in common use.

I claim as my invention—

1. The combination of the valve box or chamber A, rod B, support C, and lining D, substantially as described.

2. The combination, with the packing-receptacle and the stuffing-box cover, having bearing-surfaces arranged in juxtaposition, so as to allow of the sliding of the former upon the latter, of the ring of Babbitt or other anti-frictional metal inserted in the face of the packing-receptacle, so as to move therewith and bear upon the face of the stuffing-box cover, substantially as described.

3. In a metallic packing for valve or other rods, the combination, with the packing-rings, of a tapering coiled metallic spring having at each end two or more of its coils or turns brought in contact, to form abutments or bearings, substantially as described.

4. The combination of the valve box or chamber A, support C, spring F, follower G, packing-rings H I, packing-receptacle J, and covers M O, substantially as described.

5. In a metallic packing for valve or other rods, the combination of the packing-receptacle J and the stuffing-box cover M, provided with the brass lining P, substantially as described.

EDWIN PEAR MONROE.
